UNITED STATES PATENT OFFICE.

WERNER ARNOLDS, OF PORTA WESTFALEN, GERMANY, ASSIGNOR TO F. H. WESTER-SCHULTE, OF CHICAGO, ILLINOIS.

VEHICLE SPRING.

Application filed January 9, 1924. Serial No. 685,278.

This invention relates to vehicle springs, and the purpose of the invention is to provide suitable springs for eliminating or reducing the jars of vehicles when passing over rough roads, and also for eliminating or reducing the undesirable effects of the rebounds of the vehicle as it is forced upwardly or downwardly by the springs. Other objects of the invention will be apparent from a consideration of the accompanying drawings and the following description thereof.

Of the drawings, Fig. 1 is a rear elevation of a vehicle chassis with springs attached thereto, which embody the features of my invention; and Fig. 2 is a section along the line 2—2 of Fig. 1.

In carrying out my invention I replace the ordinary elliptical or semielliptical leaf springs, or other springs, with coil springs so arranged as to provide resilient means tending to prevent relative movement of the axle and the chassis frame, and thus to reduce the undesirable effects when the wheels go over obstructions or pass into depressions, and also to reduce the effects of the rebound of the chassis in either case. While I show and describe herein particular details of my preferred form of apparatus, yet it is to be understood that modifications may be made in details thereof without departing from the spirit of my invention as set forth in the attached claims.

The frame 3 of the vehicle, which in this instance is an ordinary automobile, supports brackets 4 to which are pivoted cylinders 5, having restricted open ends 8. In the cylinders 5 are pistons 6 having stems 7. Between the restricted end and the pistons in each cylinder is a compression spring 9. The upper ends of the pistons are pivoted to a head 10 of a piston stem 11. To the other end of the piston stem 11 is a piston 12 which is mounted in the cylinder 13. The cylinder 13 is fixed by any suitable means such as the casing 14 to the axle 15 of the car, and a compression spring is mounted in the cylinder 13 on the stem 11.

From a consideration of this apparatus, it will appear that if the wheels 17, which are mounted on the ends of the axle 15, strike an obstruction so as to elevate one or both ends of the axle, the springs 9 will be compressed as the axle 15 will be forced towards the frame 3; and the pistons 6, be-

ing connected by the piston stems 7 to the head 10, will be forced upwardly with the axle. This will give a cushioning effect which will materially reduce the jar on the frame. The springs, however, will, as is usual in such cases, tend to force the frame upwardly somewhat, but this tendency will be overcome or reduced by the effect of the compression spring 16 which will be compressed thereby. On the other hand, if one of the wheels passes into a depression the tendency of the frame to pass downwardly will be reduced by the compression spring 9 in the cylinders 5; and at the same time the compression spring 16 will reduce the effect of the rebound as the frame is forced upwardly by the springs 9. In a general way this describes the action of the springs with reference to the relative movement of the frame and the axle.

However, to assist in the action of the springs and to reduce the noise and friction thereof, the various cylinders are closed and may be filled with any suitable liquid such as lubricating material or glycerine, and each piston has an opening 20 which allows the liquid to pass from one side of the piston to the other as it operates. This not only lessens any wearing tendencies of the parts, but it cushions the pistons, thus reducing the strain on the springs, and also the tendency of the pistons to strike against the ends of the cylinders. Also, I place in the lower end of each cylinder a disk 21 of yielding material such as rubber which still further reduces the jar and noise of the pistons as they strike on the ends of the cylinder.

In order to avoid any liability of the frame striking the head 10 or other portions of the apparatus, the brackets 4 have arms 22 which curve outwardly from the frames and thus the beams of the frame are at one side of the spring apparatus and cannot strike the head 10. By the various arrangements for preventing rebounds and jars the severe stress which ordinarily would affect the springs is eliminated or so reduced that liability of fracturing the springs is substantially eliminated. The cushioning effect of the liquid in the cylinders and of the rubber disks 21 and the counter effects of the spring 13 with reference to the springs 9, eliminates the stress on the springs sufficiently to prevent fractures thereof.

I claim as my invention:

1. In a vehicle having a frame and an axle, a cylinder pivoted to said frame and having a restricted open end, a piston in said cylinder, a stem fixed to said piston and projecting out of said open cylinder end, a compression spring in said cylinder between said piston and restricted end, and resilient means pivotally connecting the projecting 10 end of said stem with said axle, said means comprising a second cylinder with its closed end rotatably mounted on said axle, and having a restricted open end, a piston in said second cylinder, a stem fixed to said piston 15 and projecting from said second cylinder, and means pivotally connecting the projecting ends of said two stems.

2. In a vehicle having a frame and an axle, a cylinder pivoted to said frame on each side of said axle and having a restricted upwardly extending open end, a piston in each of said cylinders, a stem fixed to each of said pistons and projecting upwardly out of said open cylinder end, a compression 25 spring in each of said cylinders between said piston and restricted end, resilient means pivotally connecting the projecting end of each of said stems with said axle, said means comprising a second cylinder with its closed end 30 rotatably mounted on said axle, and having a restricted open end, a piston in said second cylinder, a stem fixed to said piston and projecting from said second cylinder, means pivotally connecting 35 the projecting ends of said three stems, and a liquid in each of said cylinders.

3. In a vehicle, a frame and an axle, two cylinders pivoted to said frame and positioned above but on opposite sides of said axle, the lower ends of said cylinders being closed and the upper ends having restricted 40 openings, a piston in each cylinder, a stem fixed to each piston and projecting upwardly from its cylinder, a compression spring on each stem between the piston and the upper end of the cylinder, and resilient means connecting the projecting end of each of said stems to said axle.

4. In a vehicle, a frame and an axle, two cylinders pivoted to said frame and positioned above but on opposite sides of said axle, the lower ends of said cylinders being closed and the upper ends having restricted 45 openings, a piston in each cylinder, a stem fixed to each piston and projecting upwardly from its cylinder, a compression spring on each stem between the piston and the cylinder end through which the stem projects, and resilient means connecting each of said stems to said axle, said means comprising a third cylinder with its closed end 50 rotatably fixed to the axle and with its other end open but restricted, a piston in said third cylinder, a stem fixed to the piston of said latter cylinder and projecting from the cylinder, a coil spring within said cylinder encircling said stem, the projecting ends of all of said stems being pivotally connected.

In testimony whereof, I hereunto set my hand.

ING. ARNOLDS, (WERNER.)
